Farmington, Mich. 48024

Filed May 10, 1967, Ser. No. 7,057

Term of patent 14 years

(Cl. D22—27)

FIG. 2

FIG. 3

FIG. 5

FIG. 6

FIG. 4

FIG. 1 is a perspective view of a fishing lure, showing my new design.

FIG. 2 is a side elevational view thereof.

FIG. 3 is a top plan view.

FIG. 4 is a bottom plan view.

FIG. 5 is a left end elevational view.

FIG. 6 is a right end elevational view.

The characteristic feature of my design resides in the gradual twist of the lure body, in the central portion thereof, as best illustrated in FIGURES 1, 3 and 4 of the drawings.

I claim:

The ornamental design for a fishing lure, substantially as shown and described.
